UNITED STATES PATENT OFFICE.

WILLIAM AUGUST MILLER, OF MONACA, PENNSYLVANIA.

FUSE.

Application filed April 1, 1921. Serial No. 457,745.

To all whom it may concern:

Be it known that I, WILLIAM A. MILLER, a citizen of the United States, and resident of Monaca, in the county of Beaver and 5 State of Pennsylvania, have invented certain new and useful Improvements in Fuses, of which the following is a specification.

My invention relates to improvements in electric fuses of the removable cartridge 10 type of construction, and it consists in the combinations, constructions and arrangements herein described and claimed.

An object of my invention is to provide a magazine fuse in which a plurality of extra 15 fusible elements are held in reserve and in position to be used selectively or successively to carry the load of an electric current.

A further object of my invention is to provide a magazine fuse which is adapted 20 to hold a plurality of fusible elements, any one of which can be rendered operative without disassembling the fuse and without the use of any tools.

A still further object of my invention is 25 to provide a magazine fuse which can be quickly and easily reloaded without the use of any tools and which is thoroughly practical commercially.

Other objects and advantages will be apparent from the following description, and the novel features of the invention will be particularly outlined in the appended 30 claims.

My invention is illustrated in the accompanying drawing, forming a part of this application, in which—

Figure 1 is a perspective view of a fuse embodied in the invention,

Figure 2 is a longitudinal section through 40 the fuse shown in Figure 1,

Figure 3 is a transverse section along the line 3—3 of Figure 2,

Figure 4 is a perspective view, showing the parts of the fuse in disassembled 45 position, and

Figure 5 is a perspective view of a contact member comprised in the fuse.

Referring now to the drawings, the numeral 1 designates a cylindrical core which 50 is made of any suitable insulating material and which has an axial bore 2 formed therethrough. The core 1 has a plurality of spaced parallel grooves 3 formed in its peripheral wall to extend longitudinally

thereof and each being formed with a 55 counter-bore 4 at one end and a counter-bore 5 at its other end, the counter-bore 5 having a greater length than the counter-bore 4.

A contact member or conducting head which is adapted to be positioned contiguous 60 to the end of the core 1 provided with the counter-bore 5 comprises a substantially cylindrical body 6 having an integral annular portion 7 extending from one end and being provided with a contact projection 8 and with spacing projections 9 which are 65 of less length than the contact projection 8. An annular shoulder 10 is thus defined at the juncture of the body 6 and the annular extensions 7.

A bushing made of insulating material 70 comprises a body 11 conforming in contour to and interfitting an axial socket 12 in the outer end of the body 6 so that an annular extension 13 to the body of the bushing is 75 received in a bore 14 which extends from the bottom of the socket 12 through the extension 7, as shown. The socket 12 is non-circular in sectional contour as is the outer 80 wall of the body 11. The latter is provided with a squared axial opening 15 extending for a distance from its outer end and then being reduced at 16 and merged into an axial bore 17 extending through the extension 13. The bore 17 and the bore 2 of the 85 core 1 are substantially equal diametrically.

A conducting head or contact member 90 adapted to be arranged at the end of the core 1 provided with the counter-bore 4 comprises a substantially cylindrical body 18 having a cylindrical extension 19 at its inner end, thereby defining an annular shoulder 20. The body 18 is provided with a non-circular opening or socket 21 extending axially from its outer end for a distance and 95 then being reduced at 22 and merged into an axial bore 23 extending through the extension 19, whereby the latter is annular in form.

A bushing made of insulating material 100 comprises a body 24 interfitting the socket 21 and being provided with a reduced extension 25 at its inner end, which extension is adapted to the bore 23. The body 24 of the bushing is provided with a socket 26 of 105 non-circular cross sectional contour which extends axially from the outer end of the body 24 for a distance and is merged at 27

into an axial bore 28 extending through the extension 25. The axial bore 28 is substantially equal diametrically to the bore 2 through the core 1.

5 A sleeve 29 made of an insulating material is adapted to encompass the core 1 and to be rotatably mounted upon the annular extensions 7 and 19 of the conducting heads at the opposite end of the core. The 10 sleeve 29 has a longitudinally extending slot 30 formed therethrough, which slot is adapted to register with a selected groove 3 of the core 1 when the latter is disposed within the sleeve 29 and is provided with 15 enlarged end portions 31—31 adapted to overlie the counter-bores at the opposite ends of the groove 3 with which the slot 30 is in registry.

The parts of the fuse described so far are 20 held in assembled relation by a bolt 32 having a head 33 adapted to the socket 15 and a shank adapted to be journaled in the aligned bores 17, 2 and 28, and to threadedly engage a nut 34 which is adapted to the 25 socket 26. In assembling the fuse, the bushings are placed in the respective conducting heads or contact members and the bolt 32 is projected through the bore 17 so that the head 33 is disposed within the 30 socket 15 in abutting relation to the shoulder 16. The core 1 is then mounted upon the shank of the bolt and arranged relatively to the body 6 so that the contact 35 projection 8 extends into one of the counter-bores 5. The sleeve 29 is then slipped over the core 1 and the extension 7 into abutting relation to the shoulder 10. The body 6 with the bushing therefor fitted therein and with the nut 34 disposed in the socket 26 is now 40 held against turning and the projecting end portion of the shank of the bolt is moved through the bore 28 into engagement with the nut 34. The bolt is then turned by rotating the body 6 until the proximate end 45 of the sleeve 29 is mounted upon the annular extension 19 and abuts the shoulder 20, the opposite end of the sleeve 29 being at this time adjacent to but not necessarily in abutting relation to the shoulder 10.

50 My invention contemplates the use of fusible elements, such as indicated at 35 in the drawing. Each of the fusible elements 35 has a straight body provided with enlarged end portions or heads 36—36. The 55 body of each fusible element 35 is adapted to each groove 3 of the core 1 so that one of the heads 36 is disposed within and fills the counter-bore 4 at the end of the groove 3 while the other head 36 is disposed within 60 the counter-bore 5 of the groove 3 and terminates at a distance from the outer end of the counter-bore 5 equal to the length of the contact projection 8.

To load the fuse, the sleeve 29 is rotated 65 relatively to the core 1 until the slot 30 is

in registry with one of the grooves 3. One of the fusible elements 35 is then inserted through the slot 30 into the underlying groove 3 and is disposed in the latter and in the counter-bores at the ends thereof in 70 the manner described. The sleeve 29 is then rotated until the slot 30 is in registry with the next groove 3 of the series and a fusible element 35 is arranged in the groove 3. The operation is continued until fusible elements 75 have been placed in all chambers of the core. The sleeve 29 is then turned until the slot 30 is not in registry with any one of the grooves 3. The fuse is now loaded and is put into condition for service in the following manner. The body 6 is held against turning and the body 18 is turned to tighten 80 the nut on the bolt 32 so that the core 1 will be clamped between the head of the fusible element disposed within the counter-bore 4 85 and the spacing projections 9 while the contact projection 8 will be in contact with the head 36 of one fusible element while all the heads of the fusible elements which are disposed within the counter-bores 4 will be 90 in contact with the annular extension 19 to the body 18. It will thus be manifest that an electric current may pass from the contact member 18 to all the heads 36 disposed in the counter-bores 4 and a selected fusible element to the contact projection 8 and along the latter to the body 6, or vice versa. 95

When the fusible element in operative position has "blown", a reserve fusible element held within one of the chambers of the core is rendered operative as follows. The nut 34 is loosened by turning the body 6 while the body 18 is held until the projection 8 can be withdrawn from the chamber containing the "blown" fusible element. 100 The body 6 is then rotated until the projection 8 is in position to enter a selected chamber in which a reserve fusible element is disposed. The nut 34 is then tightened in the manner described to clamp the projection 8 against the head of the selected fusible element. If desired, the sleeve 29 may be rotated until the slot 30 is in position with the chamber containing the fusible element to be rendered operative and the 105 position of the contact projection 8 in relation to the selected fusible element conveniently observed. 110

It will thus be manifest that a great economy is effected by my invention. The core 1 115 may be formed with any desired number of chambers for the fusible elements and the fuse in which the core is comprised used continuously with but such interruptions to the service for which intended as are necessary to render the several fusible elements 120 operative selectively or successively in the manner described and to permit of the re-loading of the fuse when certain or all of the fusible elements have been "blown." 125 130

The expense attendant upon the use of my improved fuse in the manner described will be relatively small, being restricted to the cost of the fusible elements used during a given period of service. The dimensions of the parts of my improved switch are preferably such as to render the switch suitable for use with clips and fittings of standard sizes.

Obviously, my invention is susceptible of embodiment in forms other than that in which illustrated in the accompanying drawing, and I therefore consider as my own all modifications and adaptations of the form of the device disclosed herein which fairly fall within the scope of the appended claims.

Having thus described the invention what I claim is:—

1. A fuse comprising a substantially cylindrical core made of insulating material and having an axial bore, said core being formed with a plurality of spaced parallel grooves extending longitudinally of the core and being counter-bored at the ends of the core, the counter-bore at one end of each groove being longer than the counter-bore at the opposite end of the groove, fusible elements adapted to be disposed in said grooves and having enlarged end portions disposed in the counter-bores at the ends of said grooves, the smaller counter-bores being completely filled and the larger counter-bores being partially filled by the portions of the fusible elements disposed therein, the fusible elements terminating short of the outer ends of the longer counter-bores, contact members adapted to abut the opposite ends of the core, the contact member for the end of the core provided with the longer counter-bores having a projection adapted to enter a selected counter-bore to contact the fusible element disposed therein, and means extending through the axial bore of said core and connecting the contact members for releasably holding said contact members in abutting relation to the ends of said core and with the said projection of one of the contact members disposed in a selected counter-bore.

2. A fuse comprising a substantially cylindrical core made of insulating material and having an axial bore, said core being formed with a plurality of spaced parallel grooves extending longitudinally of the core and being counter-bored at the ends of the core, the counter-bore at one end of each groove being longer than the counter-bore at the opposite end of the groove, fusible elements adapted to be disposed in said grooves and having enlarged end portions disposed in the counter-bores at the ends of said grooves, the smaller counter-bores being completely filled and the larger counter-bores being partially filled by the por-

tions of the fusible elements disposed therein, the fusible elements terminating short of the outer ends of the longer counter-bores, contact members adapted to abut the opposite ends of the core, the contact member for the end of the core provided with the longer counter-bores having a projection adapted to enter a selected counter-bore to contact the fusible element disposed therein, means extending through the axial bore of said core and connecting the contact members for releasably holding said contact members in abutting relation to the ends of said core and with the said projection of one of the contact members disposed in a selected counter-bore, and an insulating sleeve spanning said contact members and concentric with said core, said sleeve having an opening therethrough adapted to register with said grooves, as said sleeve is rotated relatively to the core and through which the fusible elements can be fed to said grooves.

3. A fuse comprising a core made of insulating material and formed with a plurality of spaced grooves in its outer surface extending longitudinally thereof, each of said grooves being provided with a shoulder located at a determined distance from the adjacent end of the groove, the shoulders adjacent to opposite ends of the core being located at different distances from the corresponding ends of the core, a fusible element for each groove, each fusible element being adapted to be disposed in said groove and having end portions adapted to engage with said shoulders to hold the fusible element within the groove so that one end of the fusible element is flush with the corresponding end of the core and the other end of the fusible element is spaced from the second end of the core, a contact member for the end of the core having the shoulders located relatively near to the end, said contact member being adapted to abut the adjacent ends of the fusible elements, a contact element for the second end of the core and having a projection adapted to be projected into a selected one of the grooves into abutting relation to the adjacent end of the fusible element in the said one groove, and cooperative means carried by the core and the contact members for releasably holding the latter in abutting relation to the opposite ends of the core.

4. A fuse comprising a core made of insulating material and formed with a plurality of spaced grooves in the outer wall thereof, said grooves extending the entire length of the core, a fusible element for each groove, said fusible element being adapted to be disposed in the groove and being shorter than the groove, said grooves and said fusible elements being formed to co-engage in such manner as to hold the fusible elements flush with one end of the core and short of the

opposite end of the core, a contact element at the first named end of the core in abutting relation to the adjacent ends of all the fusible elements; a contact member at the 5 opposite end of the core having a relatively long projection extending into a selected one of the grooves into abutting relation

to the fusible element therein and having spacing members engaging with the adjacent end of the core, and means for releasably holding the contact members clamped against the ends of the core.

10

WILLIAM AUGUST MILLER.
